Primary Examiner — Elizabeth J Oswecki(74) *Attorney, Agent, or Firm* — Banner & Witcoff, Ltd.**CLAIM**

The ornamental design for a shoe, as shown and described.

DESCRIPTION

The FIGURE is a photographic side view of a shoe showing my new design.

The broken lines immediately adjacent to the photographic area represent the bounds of the claimed design and form no part thereof. The lighter grey portions are for the purpose of illustrating portions of the shoe which form no part of the claimed design.
